JOHN L. MILTON, OF CHICAGO, ILLINOIS.

INDUCTOR-GENERATOR FOR IGNITION PURPOSES.

1,051,373.

Specification of Letters Patent. Patented Jan. 21, 1913.

Application filed June 17, 1907. Serial No. 379,485.

To all whom it may concern:

Be it known that I, JOHN L. MILTON, a citizen of the United States, residing at Chicago, in the county of Cook and State 5 of Illinois, have invented certain new and useful Improvements in Inductor-Generators for Ignition Purposes, of which the following is a specification, reference being had therein to the accompanying drawings.

10 This invention relates to improvements in inductor generators for ignition purposes. It is an improvement upon the apparatus for similar purposes set forth and described in my application Serial No. 357,041, filed 15 February 12, 1907, for inductor generators.

Figure 1 is a front face view of an inductor generator embodying my improvements. Fig. 2 is a section on the line 2—2, Fig. 1. Fig. 3 is a diagrammatic view showing the 20 inductor in another position than that shown in Fig. 1. Fig. 4 is a diagrammatic view showing the inductor in still another position. Fig. 5 is a diagrammatic view illustrating a modified type of inductor.

25 In the drawings 1, 2, indicate permanent field magnets, preferably arranged parallel to each other. These permanent field magnets may be of any suitable construction. I prefer, for the purpose of economy of cost 30 and simplicity of construction, to make up each field magnet of a plurality or group of permanent straight bar magnets 3.

35 4, 5, represent pole pieces one interposed between the positive poles of said permanent magnets, and the other interposed between the negative poles of the permanent magnets. Preferably these pole pieces are made up of laminæ of metal of high magnetic permeability and susceptibility, and 40 form with the permanent magnets a substantially rectangular frame. For this purpose I have provided the same simple arrangement and correlation of the ends of the permanent magnets and the ends of the pole pieces, shown and described in my application 45 for Letters Patent hereinbefore referred to, namely, the straight bar magnets forming each group of magnets increase in length from the innermost one outward, 50 and are so arranged as to form a series of steps 6 at either end of each permanent field magnet. The end of each pole piece is stepped to correspond with the end of the permanent magnet adjacent to it.

55 7 are U-shaped clips, each fitted over the

end of a permanent field magnet and the end of a pole piece adjacent thereto, and secured to the pole piece in any suitable manner, as for example by a rivet 7'.

Each pole piece carries three inwardly 60 turned polar projections, those on the pole piece 4 being indicated by 8, 9, and 10, respectively, and those on the pole piece 5 by 8', 9', and 10', respectively. Preferably, the laminæ of which each pole piece is built 65 up are suitably stamped out to form the polar projections carried by the pole pieces.

11 is an inductor shaft. 12 is an inductor 70 suitably secured to said shaft and arranged to rotate between the polar projections on the opposite pole pieces. This inductor is preferably made up of laminæ of metal of high magnetic permeability and shaped to form four radial extensions or projections 12' arranged 90 degrees apart about the axis 75 of the shaft 12, in the form of a Maltese cross.

The polar faces of the polar projections carried by the pole pieces are each curved to the arc of a circle common to all, struck 80 from the axis of the shaft 11 as a center, and the coöperating surfaces of the projections 12' on the inductor are correspondingly curved and arranged to operate as closely adjacent to the polar faces of the 85 polar projections as mechanical conditions will permit.

The inductor shaft 11 may be supported in any suitable manner. For the purpose 90 of illustration I have shown it mounted in a bearing 13 carried by a suitable bearing standard 14.

14' is a lubricant chamber in the standard 95 14, and 14^a is an oil ring surrounding the inductor shaft in said lubricant chamber.

15 is a supporting plate of non-magnetic material for the field magnet frame. It has four radially extending arms 15' arranged 100 90 degrees apart, and each one suitably secured at its outer end, as indicated at 15^a, to the end of the adjacent polar projection. 15^b is a hollow collar or bearing on said supporting plate snugly fitted to a boss 16 on the bearing standard 14 and angularly adjustable thereabout.

17 is a set screw carried by the collar 15^b and having its inner end arranged to engage the boss 16 to hold the plate 15 and field magnet frame in any desired position 110

of angular adjustment relative to the axis of the shaft 11.

18 is a coil of insulated wire surrounding the polar projection 9, which is the middle 5 polar projection of the three carried by the pole piece 4. 19 is a coil of insulated wire surrounding the polar projection 9', the middle one of the three carried by the pole piece 5. These induction coils may be electrically connected together in any suitable 10 manner. In the drawings, I have shown a conductor 20 connecting them in series.

21 is a binding post carried by one of the arms 15' of the support 15. The free end 15' of the coil of wire 18 is connected with this binding post. The free end 19' of the coil 19 may be connected with one terminal of the ignition system for an internal combustion motor in any suitable manner. The 20 free end 18' of the coil 18 may be suitably connected to the other terminal of the said ignition system.

The magnetic fields set up by the two permanent field magnets oppose each other, the 25 direction of the lines of force for each field magnet across the gap between the pole pieces 4, 5, being always the same. When the inductor 12 is in the position shown in Fig. 1, a substantial magnetic short circuit 30 for the permanent magnets is established by the inductor across the diametrically opposite wire wound polar projections 9, 9', and the magnetic flux density through the induction coils 18, 19, is at its maximum.

35 As the inductor is rotated in the direction indicated by the arrows in the figures, the magnetic flux density through the induction coils is more or less gradually diminished, in accordance with the speed of rotation of 40 said inductor, until the diametrically opposite arms or projections 12', 12', each of which has been moving closely adjacent to one of the polar faces on the wire wound polar projections 9, 9', leave the said polar 45 projections and air gaps are established between the said wire wound polar projections and the inductor; then the magnetic flux density through the said induction coils is suddenly and rapidly diminished, this 50 diminution of magnetic flux density being emphasized and accelerated by the inductor establishing substantial magnetic short circuits for the permanent magnets outside of said induction coils, namely, across the 55 polar projections 8, 8', on one side of, and across the polar projections 10, 10', on the other side of said wire wound polar projections.

60 The inductor 12 and the polar faces on the polar projections carried by the pole pieces 4 and 5 are so shaped and correlated, that the inductor at all times establishes paths substantially equal in magnetic reluctance for both groups of permanent magnets at either side of it, as shown in Fig. 4.

In order to obtain a high peak to the electromotive force curve generated by the apparatus herein shown, I have found it desirable to so correlate the polar surfaces of the polar projections and the coöperating extensions on the inductor, that at the instant the diametrically opposite pair of extensions on the inductor leave the polar faces of the wire wound polar projections, air gaps are established between all of the polar projections on both pole pieces and the inductor, and that immediately thereafter the inductor establishes the substantial magnetic short circuits above referred to outside the wire wound polar projections. 70 To accomplish this result, in the device herein shown and described, I have made the width of the radial projections 12' carried by the inductor less than the distance between the most closely adjacent points at 75 either end of the polar face of each wire wound polar projection, and the polar face of the polar projection carried by the same pole piece adjacent to it, as shown in Fig. 3.

It will be noted that the polar projections 80 and inductor are so correlated that the results obtained will be the same when the inductor is turned in either direction, clockwise, or anti-clockwise, so that the apparatus may be readily accommodated to a reversible motor. Furthermore, with this construction, the inductor may be oscillated, if desired, rather than rotated.

In Fig. 5 I have illustrated a modified type of inductor over that hereinbefore described, in that the radial extensions on this modified inductor are of sufficient width to close the magnetic circuit across the unwound polar projections before they leave the wire wound polar projections and establish air gaps between the latter and the inductor. 100

What I claim is:—

1. In an inductor-alternator, the combination of a magnetic field-structure, provided with a pair of oppositely disposed pole-pieces, three polar projections carried by each pole-piece, a winding on the middle polar projection of each pole-piece, the two polar projections at either side of the wound 110 projection being unwound, and an inductor substantially in the shape of a Maltese cross, arranged to move in proximity to said polar projections to vary the distribution of the magnetic flux therethrough. 115

2. In an inductor-alternator, the combination of a magnetic field-structure provided with a pair of oppositely disposed pole-pieces, three polar projections carried by each pole piece, the polar faces of said projections being arranged in the arc of a common circle, a winding on the middle polar projection of each pole-piece, the two polar projections at either side of the wound projection being unwound, and an inductor hav- 120 125 130

ing four arms movable in proximity to said polar faces to vary the distribution of the magnetic flux therethrough, the width of said arms at their outer ends being less than 5 the distance between adjacent polar faces.

3. In an inductor-alternator, the combination of a pair of oppositely disposed permanent bar-magnets, pole-pieces for connecting the poles of like polarity, three polar projections carried by each pole-piece, a winding on the middle polar projection of each pole-piece, the two polar projections at either side of the wound projection being unwound, and an inductor substantially in the shape 10 of a Maltese cross arranged to vary the distribution of the magnetic flux through said polar projections, said inductor in one position establishing a substantial magnetic short-circuit across said wound polar projections, and in another position establishing 15 a substantial magnetic short-circuit across said unwound polar projections.

4. In an inductor-alternator, the combination of a magnetic field-structure provided 20 with a pair of oppositely disposed pole pieces, three polar projections carried by each pole piece, a winding on the middle polar projection of each pole-piece, the two polar projections at either side of the wound 25 projection being unwound, a plate of non-magnetic material suitably connected to said unwound polar projections for supporting the field-magnet structure, and an inductor arranged to move in proximity to said polar 30 projections to vary the distribution of the magnetic flux therethrough, said inductor in one position establishing a substantial magnetic short-circuit across said wound polar projections, and in another position establishing 35 a substantial magnetic short-circuit across said unwound polar projections.

5. In an inductor-alternator, the combination of two oppositely disposed groups of 40 permanent bar-magnets, pole-pieces for connecting the poles of like polarity, said pole-pieces being each recessed at either end to receive the adjacent end of one of the magnets, and a plurality of U-shaped clips arranged 45 to straddle each one end of a pole-piece and the group of magnets in contact therewith, and means for suitably securing said clips to the pole pieces.

6. In an inductor-alternator, the combination 50 of a pair of oppositely disposed permanent field-magnets, pole-pieces for connecting the poles of like polarity, three polar projections carried by one of said pole-pieces, a winding on the middle polar projection, the two polar projections at either 55 side of the wound projection being unwound, and an inductor arranged to move in proximity to said polar projections to vary the distribution of the magnetic flux there- 60 through, said inductor in one position estab-

lishing a substantial magnetic short-circuit through said winding, and in another position establishing a substantial magnetic short-circuit across said unwound polar projections. 70

7. In an inductor-alternator, the combination of a magnetic field-structure provided with a pair of oppositely disposed pole-pieces, three polar projections carried by each pole-piece, windings on the middle 75 polar projections, the other of said polar projections being unwound, and an inductor arranged to move in proximity to said polar projections to vary the distribution of the magnetic flux therethrough, said inductor in one position establishing a substantial magnetic short-circuit simultaneously through both windings, and in another position establishing 80 a substantial magnetic short-circuit simultaneously through all four unwound polar projections. 85

8. In an inductor-alternator, the combination of a pair of oppositely disposed permanent field-magnets, pole-pieces for connecting the poles of like polarity, three polar 90 projections carried by each pole-piece, windings on two of said polar projections, the other of said polar projections being unwound, and an inductor arranged to move in proximity to said polar projections to vary the distribution of the magnetic flux therethrough, said inductor in one position establishing a substantial magnetic short-circuit simultaneously through both windings, and in another position establishing a substantial magnetic short-circuit simultaneously through all four unwound polar projections.

9. In an inductor-alternator, the combination of a magnetic field-structure provided with a pair of oppositely disposed pole-pieces, three polar projections carried by each pole-piece, windings on some of said polar projections, the other of said polar projections being unwound, and an inductor having four radial arms movable in proximity to said polar projections, said arms serving in one position to establish a substantial magnetic short-circuit through said windings, and in another position to establish a substantial magnetic short-circuit across said unwound polar projections.

10. In an inductor-alternator, the combination of a magnetic field-structure provided with a pair of oppositely disposed pole pieces, three polar projections carried by each pole piece, an inductor having four radial arms movable in proximity to said polar projections, said arms serving in one position to establish a substantially magnetic short-circuit through four of said polar projections, and in another position to establish a substantially magnetic short-circuit through the two middle polar projections, and windings so arranged on said

polar projections that the magnetic variations therethrough occur simultaneously as the inductor is rotated.

11. In an inductor-alternator, the combination of a pair of oppositely disposed permanent straight-bar magnets, pole pieces connecting the poles of like polarity, three polar projections carried by each of said pole pieces, an inductor having four radial arms movable in proximity to said polar projections, said arms serving in one position to establish a substantially magnetic short-circuit through four of said polar projections, and in another position to establish 15 a substantially magnetic short-circuit through the two middle polar projections, and windings so arranged on said polar projections that the magnetic variations therethrough occur simultaneously as the inductor is rotated.

12. In an inductor alternator, the combination of a pair of oppositely disposed permanent straight-bar magnets, pole pieces arranged between said magnets at right an-

gles thereto for connecting the poles of like polarity and forming with said magnets a substantially rectangular frame, said pole pieces and magnets lying in a single radial plane, three polar projections carried by each of said pole pieces, a winding on each 30 middle polar projection, the two polar projections on each side of the wound polar projections being unwound, and an inductor having a plurality of radial arms arranged to move in proximity to said polar projections to vary the magnetic flux therethrough, said inductor in one position establishing a magnetic short-circuit through said wound polar projections and in another position establishing a magnetic short-circuit through 35 40 said unwound polar projections.

In testimony whereof I affix my signature, in presence of two witnesses.
